US00D500599S

(12) **United States Design Patent** (10) Patent No.: **US D500,599 S**
 Callaghan (45) Date of Patent: **** Jan. 11, 2005**

(54) **TOOTHBRUSH HANDLE**

(75) Inventor: **Roberta L. Callaghan**, Fort Collins, CO (US)
 (73) Assignee: **Water Pik, Inc.**, Fort Collins, CO (US)
 (**) Term: **14 Years**
 (21) Appl. No.: **29/173,524**
 (22) Filed: **Dec. 31, 2002**
 (51) LOC (7) Cl. **28-03**
 (52) U.S. Cl. **D4/101**
 (58) Field of Search **D4/101, 104-112, D4/138; 15/143.1, 167.1, 22.1, 23-24, 28-29; 601/142; 132/308, 309, 311**

(57) **CLAIM**

The ornamental design for a toothbrush handle, as shown and described above.

DESCRIPTION

FIG. 1 is a right side perspective view of a toothbrush handle showing my new design;

FIG. 2 is a front elevation view thereof;

FIG. 3 is a left elevation view thereof;

FIG. 4 is a right elevation view thereof;

FIG. 5 is a rear elevation view thereof;

FIG. 6 is a top plan view thereof; and,

FIG. 7 is a bottom plan view thereof.

1 Claim, 4 Drawing Sheets
